Design No. 19,197, dated July 9, 1889.

No 19,197

FIG. 1.

FIG. 2.

UNITED STATES PATENT OFFICE.

CHRISTIAN H. HANSEN, OF TRENTON, NEW JERSEY, ASSIGNOR TO HENRY HUBER, OF NEW YORK, N. Y.

DESIGN FOR THE SURFACE ORNAMENTATION OF WATER-CLOSET BOWLS.

SPECIFICATION forming part of Design No. 19,197, dated July 9, 1889.

Application filed January 4, 1889. Serial No. 295,451. Term of patent 7 years.

To all whom it may concern:

Be it known that I, CHRISTIAN H. HANSEN, a citizen of the United States, residing at Trenton, in the county of Mercer, State of New Jersey, have invented and produced a new and original Design for Sanitary Earthenware, of which the following is a specification.

This is a design for the surface ornamentation of porcelain water-closet bowls and other analogous sanitary earthenware. Its leading features are the ornamental pattern extending around the upper part or rim portion of the bowl and the ornamentation for the front of the standard portion of the bowl.

15 The design is shown in the accompanying photographs, wherein—

Figure 1 is a perspective view of a double-trapped water-closet bowl the surface of which is ornamented according to my design.

20 Fig. 2 is an elevation of a single-trapped bowl, the surface ornamentation of which is also in accordance with my design.

Referring to either figure, let A designate the bowl proper, and B the standard or trap 25 portion thereof.

C is an ornamental pattern extending around the upper or rim portion of the bowl A.

D is an ornamental pattern at the front of the standard portion B.

30 The patterns C and D are executed in low relief in the two examples shown.

The pattern C consists of a succession of conventionalized floral or leaf-like figures a and b, arranged in alternation beneath a band c, which extends around the rim of the bowl. The figures a consist each of a stem branching downwardly from the band c, with an excised or palmatisected hastate leaf having in general the form of an isosceles triangle, 40 the base of which coincides with the bottom outline of said band c. The figures b consist each of a stem springing downwardly from the band c, widening into approximately the form of an arrow-head and supporting a pend-

45 ent floral figure of three petals resembling a *fleur de lis*, the lateral petals of which curve outwardly and partially fill the triangular space between the figures a a.

The pattern D consists of a conventionalized

50 figure of leaves arranged wholly above and separated from the foot of the bowl. Its exact expression varies somewhat in the two figures by reason of the different shape of the surface to which the pattern is applied. Thus in Fig. 1 it is restricted to a band of uniform 55 width extending down the curved front of the standard, while in Fig. 2, being free from such restriction, it is extended laterally at its middle portion, having the general outline approximating a diamond. In both instances 60 the figure consists of stems d d and leaves f f radiating from a central point e upwardly, downwardly, and laterally, the lines of radiation being extended straight up and down along the center and more or less curved in 65 lateral direction on the sides, as clearly shown. The leaves are of the general character of oak-leaves.

What I claim is—

1. The design for the surface ornamentation of sanitary earthenware, substantially as described, and shown in the accompanying photographs.

2. In a design for the surface ornamentation of sanitary earthenware, the described 75 design for the upper or rim portion thereof, consisting of a succession of conventionalized floral or leaf-like figures a and b, arranged in alternation and forming a border pattern C, 80 extending around the rim of the bowl, substantially as shown in the accompanying photographs.

3. In a design for the surface ornamentation of sanitary earthenware, the described 85 design for the standard portion thereof, consisting of a pattern D of stems and leaves radiating upwardly, downwardly, and laterally, and arranged above and separate from the foot of the bowl, substantially as shown in 90 the accompanying photographs.

In witness whereof I have hereunto signed my name in the presence of two subscribing witnesses.

CHRISTIAN H. HANSEN.

Witnesses:

R. O. AULICK,

THOMAS CONNOLLY.
